UNITED STATES PATENT OFFICE.

PAUL JACOB AND CURT JACOB, OF ZWICKAU, GERMANY.

BURNER FOR ACETYLENE GAS.

SPECIFICATION forming part of Letters Patent No. 731,907, dated June 23, 1903.

Application filed September 30, 1902. Serial No. 125,385. (No model.)

To all whom it may concern:

Be it known that we, PAUL JACOB and CURT JACOB, subjects of the King of Saxony, residing at Zwickau, in the Kingdom of Saxony, Germany, have invented certain new and useful Improvements in Burners for Acetylene Gas, of which the following is a specification.

This invention relates to gas-burners; and the object of the invention is to provide a simple device of this character having effective means for regulating the quantity of air to be mixed with the gas in the burner-tube, and although the improved burner is capable of advantageous use in connection with different kinds of gas it has been found satisfactory as a burner for acetylene gas.

The invention is clearly illustrated in the accompanying drawings, forming a part of this specification, and in which—

Figure 1 is a sectional elevation of a burner including our invention and showing the manner of using the same. Fig. 2 is an elevation of the burner-tube and air-regulator carried thereby. Fig. 3 is a detail in elevation of a different form of regulator.

Like characters refer to like parts in the several figures.

Referring to Fig. 1, the numeral 1 indicates a burner-tube, it having threaded into its lower end the gas-nipple 2 and being provided substantially in the same plane as the upper end of the nipple with a series of air-inlets of the usual kind. In said Fig. 1 and also in Fig. 2 the air-regulator is shown as consisting of a sleeve 3, in threaded engagement at 4 with said burner-tube. From this it will be evident that the air-regulating sleeve is vertically adjustable, whereby it may be raised or lowered across the said air-inlets in order to increase or decrease the effective area thereof and correspondingly control the amount of air flowing into the burner-tube 1. The lower end of the air-regulating sleeve is shown as bell-shaped in order to collect atmospheric air and properly direct the same through said air-inlets. The burner-tube 1 contains the superposed mixing-chambers 8 and 9 for the gas and air, respectively, the upper chamber being formed in the tube 10, fitted upon the upper side of and constituting a continuation of the burner-

tube 1. This tube 10 is connected with the usual yoke 11 or its equivalent in some familiar manner, and it is covered by a cap 55 12, having a gas-outlet 13, under which one or more disks of gauze 14, as is customary in this class of devices, may be situated. As the bell-shaped extension upon the body of the vertically-adjustable air-regulating 60 tube covers the air-inlets alluded to, it is necessary to provide some means for effecting the accurate adjustment of the body of the sleeve with respect to said inlets, and this is effectually accomplished in the following way, 65 although the invention is not limited to the means now to be described: Upon the burner-tube 1, near the lower end thereof, is a strip 7, constituting a stop and which has a vertically-elongated slot to receive a set-screw 70 tapped into said burner-tube, it being understood that the slot and set-screw provide for vertical adjustment of the strip. The upper end of said strip or stop is adapted to intersect the line of the air-inlets, and said strip 75 preferably intersects one of said air-inlets in order that its accurate adjustment can be secured. After the regulating-sleeve has been raised the strip may be adjusted so as to overlap more or less one of said inlets. When 80 the strip or stop is adjusted to the proper extent, the air-regulating sleeve will be lowered until its body strikes the upper end of the stop. It will be understood, therefore, that even though the bell-shaped extension 85 at the lower end of the air-regulating sleeve covers the air-inlets said sleeve may be accurately adjusted through the agency of the adjustable stop.

Instead of connecting the air-regulating 90 sleeve to the burner-body by a screw-threaded joint it may be united thereto in other ways. In Fig. 3 the gas-regulating sleeve 5 has in its upper portion a plurality of elongated slits, which form yieldable fingers which 95 engage the burner-body above the air-inlets therein. A gas-regulating sleeve constructed in this manner can be readily raised and lowered upon the burner-body.

Having thus described our invention, what 100 we claim is—

1. The combination of a burner-body having one or more air-inlets, a vertically-adjustable air-regulating sleeve upon the burner-

body, provided with a bell-shaped lower end, and a vertically-adjustable stop upon the burner-body arranged to be engaged by the body of said sleeve.

5 2. The combination of a burner-body having one or more air-inlets, a vertically-adjustable air-regulating sleeve upon the burner-body, provided with a bell-shaped lower end, and a vertically-adjustable stop upon the burner-body arranged to be engaged by the body of said sleeve and adapted to intersect one of said inlets.

15 3. The combination of a burner-body having a line of air-inlets, a regulating-sleeve adjustable vertically on the burner-body and having a bell-shaped lower end, and a vertically-adjustable stop, the upper end of which is adapted to be engaged by the body of the

sleeve and adapted to intersect the line of air-inlets.

4. The combination of a burner-body having one or more air-inlets, an air-regulating sleeve vertically adjustable on the burner-body, a stop, the upper end of which is adapted to be engaged by the body of the sleeve, 25 consisting of a strip having an elongated slot, and a screw passed through said slot and tapped into the burner-body.

In witness whereof we have hereunto set our hands in presence of two witnesses.

PAUL JACOB.
CURT JACOB.
